UNITED STATES PATENT OFFICE.

CAROLINE L. LEWIS AND CHARLES E. MIXER, OF BOSTON, MASSACHUSETTS.

DESIGN FOR A CLASP MEMBER.

SPECIFICATION forming part of Design No. 30,949, dated June 6, 1899.

Application filed April 26, 1899. Serial No. 714,505. Term of patent 14 years.

To all whom it may concern:

Be it known that we, CAROLINE L. LEWIS and CHARLES E. MIXER, of Boston, in the county of Suffolk and State of Massachusetts, 5 have invented a certain new and original Design for a Clasp Member, of which the following is a specification.

This invention relates to a design for clasp members; and the essential feature of the 10 design consists in the novel shape and configuration hereinafter fully described and claimed and clearly illustrated upon the drawings.

Figure 1 represents a longitudinal section through the clasp member embodying our design. Fig. 2 represents a plan view of the 15 same.

Referring to the drawings, *a* indicates the base of the clasp member, which at one end

is bent backward at *b* on its face and then toward said face at *c* to form a triangle, (looking at the same in section.) At the other end of the clasp it is bent into a circle *d*, (when seen in section.) In general appearance the clasp in longitudinal section resembles a triangle and a circle joined by a bridge which 25 forms the base of said triangle.

We claim—

The design for a clasp member substantially as shown and described.

In testimony whereof we have affixed our 30 signatures in presence of two witnesses.

CAROLINE L. LEWIS.
CHARLES E. MIXER.
